CLAIM

The ornamental design for a bottle, as shown and described.

DESCRIPTION

The features of the design will be described with reference to the following drawings, in which:

FIG. 1 is a front perspective view of a bottle, showing our new design;

FIG. 2 is a rear perspective view thereof;

FIG. 3 is a right view thereof;

FIG. 4 is a left side view thereof;

FIG. 5 is a front side view thereof;

FIG. 6 is a rear view thereof;

FIG. 7 is a top view thereof; and,

FIG. 8 is a bottom view thereof.

The contrast in shading represents a contrast in appearance only and does not represent any particular color, material, texture or finish.
